(57) **CLAIM**

The ornamental design for combined camp stove, grill, oven and smoker, as shown.

DESCRIPTION

FIG. 1 is a front elevational view of the combined camp stove, grill, oven and smoker showing my new design;

FIG. 2 is a rear elevational view thereof;

FIG. 3 is a side elevational view of one side thereof;

FIG. 4 is a side elevational view of a side opposite the side of FIG. 3;

FIG. 5 is a top plan view thereof;

FIG. 6 is a top plan view similar to FIG. 5 with the lid removed and the rack in place;

FIG. 7 is a bottom plan view thereof;

FIG. 8 is a front elevational view thereof with the upper vessel removed;

FIG. 9 is a rear elevational view with the upper vessel removed;

FIG. 10 is a side elevational view thereof showing one side thereof;

FIG. 11 is a side elevational view thereof showing a side opposite that of FIG. 10;

FIG. 12 is a top plan view thereof with the rack in place; and, FIG. 13 is a top plan view thereof with the frying pan in place.
